UNITED STATES PATENT OFFICE

FREDERICK L. FOX, OF WASHINGTON, DISTRICT OF COLUMBIA, AND FRANK C. GIBSON, OF FAIRFAX, VIRGINIA

GOLF GAME

Application filed September 10, 1929. Serial No. 391,684.

This invention relates to an improved portable golf game of a species embodying a game board whose surface is printed, painted or otherwise patterned to provide a unique and complete playing field which is intended to accommodate one or more indicators, these indicators being of special form and movable over especially designed sectors or areas of the playing field in a systematic and orderly manner from an established starting point to a remote or distant concluding point.

The operation of the structure depends on the action of a player-actuated device and has particular reference to a structural organization of this class which is made and designed to provide a novel golf game of the type shown in our co-pending application for patent designated as Serial Number 322,885 and filed under date of November 30, 1928.

The novelty of the invention embodied in this application is predicated upon refinements, revisions and improvements made on certain of the details of the complete game mentioned in our co-pending application above-identified.

In order to obtain a clear and comprehensive understanding of the features included in this particular case, we deem it advisable to mention briefly the general idea and construction of the golf game shown and described in the aforesaid application.

In the latter case we provide a base in the nature of a game board, and this is preferably in the form of a low table constructed to rest firmly on a floor or other support at a suitable elevation. The playing face of the board is designed and charted to represent a miniature golf course. Associated with, and systematically movable over the distinguishable sectors of this golf course are movable indicators which are fashioned to represent actual golf balls in motion as they are propelled over the playing field.

In the pending application mentioned, one or more impact devices are provided and are constructed to be actuated by the players. Incidentally, the game is constructed to permit a number of performers to play at one

Each of the impact devices includes a movable impact element (preferably a regulation golf ball) intended to be actuated by a blow from a conventional golf club and constructed to operate in conjunction with and coincident to the golf ball indicators in proper relation so that the indicators automatically and properly record the degree of movement and the power of the blow imparted to the impact element, whereby the indicators are caused to move a distance in proper proportion to the power of the blow imparted to said impact element.

Considering further the game constituting the subject matter of our co-pending case, it will be observed that it comprises a game board which has its face provided with indicia representing a miniature golf course which includes a plurality of successive sectors, and each sector in itself includes a teeing ground, a remote putting green and cup, and an intervening fairway. In addition, we provide a plurality of individual and distinguishable indicators in the form of golf balls which are successively movable along the fairway in each sector to and beyond the cup on the green. Embedded in the fairway is a plate which has a plurality of longitudinal slots formed in it and underneath of the slots are propulsion cables. The field indicators are constructed for detachable connection with these cables.

Since developing the original propulsion cable and detachable prong connection between the indicator balls and the cable, we have found it practicable and expedient to incorporate in this part of the game certain refinements which, it is believed, render the improved game more satisfactory, efficient, and dependable in operation.

Briefly, the improved arrangement is characterized by a new type of bed plate which is mounted on the table and provided with guideways. Movable in each guideway is a power actuated drive chain of a special type rendering it especially adaptable for use in an arrangement of this kind. Then too, there is a novel type of golf ball indicator provided for cooperation with the companion drive chain.

By way of contrast, the improved indicator propulsion means, which constitutes the principal novelty of this invention, is distinguishable in that an entirely new form of operating connection is had between the indicator and the especially constructed drive chain, this being in the form of a positive driving connection of a quick detachable type.

10 A further feature of the improvement is the provision of a cushioning felt covering for the table, which minimizes noise and enhances the appearance of the construction.

15 A still further feature of the improvement is the construction of the indicator which includes a rotatable ball, provided with a view toward securing more realistic results in that as the indicator travels along the fairway, the ball, constituting a part thereof, will roll.

In the drawing:

Figure 1 is a fragmentary top plan view of a portion of the game board with portions broken away to disclose the driving pulley assembly.

Figure 2 is a section taken on the line 2-2 of Figure 1.

30 Figure 3 is a sectional view taken on either of the lines 3-3 of Figures 1 and 2 respectively.

Figure 4 is a detail side elevational view of the indicator per se.

35 Figure 5 is an enlarged longitudinal section through the flexible driving chain.

Referring now to the drawing by reference numerals, it will be observed that 6 designates generally a base which, as before stated, is in the nature of a low leg equipped 10 table including a game board or base 7 which occupies a plane close to the floor or other surface on which the structure is supported. In this application we have shown a fragmentary portion of the game board which 15 (for sake of clearness) merely includes a single sector on the playing field, and as before mentioned this sector includes the usual teeing ground at the left hand end, here generally designated at 8. At this same end are 20 colored disk-like markers 9, 10, 11 and 12 which are in registry with the left hand ends of the guideways for the field indicating means. We have shown two indicators positioned in Figure 1 and it will be observed 25 that the indicator is generally designated by the reference character 13.

We might state that the markers 9 to 12 inclusive are of appropriate distinguishable colors to correspond with like colors embodied in the indicators to render the playing of the game more systematic. In Figure 1 the fairway is that portion which includes the longitudinal guideways for the indicators. It will be noted that these guideways extend from the teeing ground along

the fairway to the receiving cup (not shown) at the right hand end of the fairway.

The reference character 14 designates a felt covering for the top of the table and this is provided with slots 15, 16, 17 and 18 which 70 overlie the four parallel longitudinal guideways.

The reference character 19 designates generally a metal bed plate which is here shown as constructed to fit into a correspondingly 75 shaped opening cut in the board 7, and this plate is formed with marginal attaching flanges 20 secured by screws or the like 21 to the bottom of the board. This is clearly shown in Figure 2. The plate is formed 80 with spaced parallel depressions 22 which function as the guideways for each drive chain 23. These guideways are of channel-shaped open-ended configuration and the chain slides along the bottom of the channel 85 as is obvious from Figure 3.

Particularly do we emphasize the utilization of flexible drive chains of the character indicated generally by the reference characters 23. As seen in Figure 5 each chain 90 is made up of a multiplicity of hollow balls 24 coupled together by headed connecting pins 25. This provides an unusual and a highly desirable type of driving chain or cable in that it facilitates application and 95 removal of the indicators to expedite their exchange from one area or sector to the next and so on. The indicators are bodily lifted up when it is desired to remove them and then simply returned or slipped down into the 100 guideway and engaged with the companion drive chain in an easy and expeditious style. Therefore, we provide a positive, yet quick 105 detachable connection between the chain 23 and its complemental indicator.

For sake of completeness in Figure 1 we illustrate a pulley carrying shaft 26 which is journaled for rotation in bearings 27. There are four pulleys 28 mounted on their shaft and the various driving chains 23 have 110 operating connection in alinement therewith. In addition there is a worm as at 29 on the shaft which is driven from an electric motor (not shown). The details of the power supply means are not described in this 115 application. The gist of the invention is in the construction of the especially designed propulsion or drive chains 23, the guide channels in the bed plate 19 and the especially constructed indicators 13.

Each indicator includes a centralized carrier plate whose lower end portion 30 (see Figure 3) is designed to form what may be designated as a driving foot or segmental rack. This is so made as to permit it to be 125 slipped down into the guide channel 22 between the side walls thereof. The lower edge is serrated to provide driving teeth as at 31 in Figure 4 and these teeth engage the balls 24 so that the carrier is moved along with 130

the drive chain 23. The upper end portion of the carrier plate is of disk-like form as at 32 and formed with a relatively large central hole 33 through which a comparatively small pin 34 passes. This pin serves to couple together the semi-spherical half-sections 35 of the rotatable indicator ball. This loose pin connection allows the sectional ball, which is made of lead or other weighty material to rest on the felt 14 as seen in Figure 2. In fact the ball has rolling contact with the felt and the result is that as the chain moves the indicator along longitudinally of the guideway, the ball rolls to add to the realistic results of the game.

It will be observed that the segmental rack or foot 30 is in the nature of a pendant on the lower end portion of the carrier plate and fits telescopically into the companion guide channel. The rack teeth merely rest on the balls of the drive chain 23. The points of the teeth are nested in between the balls 24 and the connecting pins 25. The indicator is quite weighty and sufficient weight is brought to bear on the toothed rack to cause the teeth to readily find their proper positions by easily settling in place. This provides the desired drag action of the chain pulling the indicator along in the channel. Inasmuch as the so called rack 30 merely rests upon the chain the entire indicator can be readily and bodily removed from one channel and exchanged or transferred to a different channel in the next sector on the golf course. This affords an absolute and positive drive for the indicator and at the same time permits the desired interchangeability in the structure. In addition we wish to mention a pawl and ratchet effect produced by the peculiar meshing of the teeth 31 with the balls 24 of the driving chain. For instance when the indicator reaches the terminal end of the guideway in which it moves it does not and must not repel the ceaseless motive action of the chain. In fact, the arrangement is so unique that the toothed foot 30 responds to the continued driving action of the chain by allowing it to carry on while the indicator stays put and merely rides over the balls 24.

The dominating characteristics of the improved field indicator arrangement or assembly are the especially designed bed plate having the open-ended channel-shaped guideways, the slot equipped felt for cushioning and friction driving purposes, the flexible ball and pin drive chain arrangement, and the peculiarly constructed indicator distinguished by the rolling ball and the tooth equipped driving foot.

The advantages which accrue from this revised arrangement will be quite clear to persons skilled in the art to which the invention relates. Therefore, a more lengthy description is regarded as unnecessary.

We claim:

1. In a golf game of the class described, in combination, a game board equipped with a playing field having a longitudinally extending guideway, an indicator movable longitudinally in said guideway, and a separable drive chain mounted below said guideway and contacting with said indicator to move the same, said drive chain being of a flexible nature and including a multiplicity of 70 balls connected together by headed coupling pins.

2. In a golf game of the class described, in combination, a game board equipped with a playing field having a longitudinally extending guideway, an indicator movable longitudinally in said guideway, and a drive chain mounted below said guideway, said drive chain being of a flexible nature and including 80 a multiplicity of balls connected together by headed coupling pins, said indicator including a portion having quick detachable and driving connection with said balls.

3. In a golf game of the class described, a base having a bed plate mounted thereon, said bed plate being provided with at least one longitudinally extending depression providing an open-ended guide channel, a propulsion element slidable in the bottom of 90 said channel, an indicator including a golf ball representation and a carrier therefor, said carrier including a portion extending down into said channel and detachably connected with said propulsion element.

4. In a golf game of the class described, a base, a bed plate mounted on said base and provided with a plurality of longitudinally extending spaced parallel open-ended channel-shaped portions constituting guideways, indicator propulsion chains mounted for 100 movement in each guideway, and individual operating means for said chains.

5. In a golf game of the class described, a base, a bed plate mounted on said base and provided with a plurality of longitudinally 110 extending spaced parallel open-ended channel-shaped portions constituting guideways, indicator propulsion chains mounted for movement in each guideway, and individual operating means for said chains, each chain being of flexible construction and including a multiplicity of closely spaced hollow balls connected together by headed coupling pins.

6. In a golf game of the class described, a game board, a bed plate carried by said board and including a plurality of longitudinally 120 extending spaced parallel open-ended guideways of channel-shaped cross section, an individual ball and pin flexible driving chain slidable in the bottom of each guideway, and a plurality of individual indicators for each guideway, each indicator including a golf ball indicia and a tooth equipped carrier plate, said plate extending down into its 125 companion guideway to permit the teeth to 130

thereof to have detachable driving connection with the balls of the complemental chain.

7. In a golf game of the class described, a game board having a playing field equipped with a sector of a predetermined character having a guideway, propulsion means associated with said guideway, and an indicator having operating connection with said propulsion means, said indicator including a rotatably mounted golf ball representation having rolling contact with the game board, and a cushion-like felt covering for said game board interposed between said golf ball representation and the top of the board.

8. In a structure of the class described, a game board having a sector designed to represent a teeing ground, a golf ball receiving cup and putting green and an intervening fairway, said fairway embodying a longitudinally extending guideway, a propulsion element suspended beneath said guideway, and an indicator movable along said guideway by contact with said element and including a rotatably mounted ball having rolling contact with said game board.

9. As a new product of manufacture, an indicator for use and association with a golf game of the class described comprising a carrier having a tooth equipped foot adapted for driving and detachable connection with a propulsion chain, and a rotatable golf ball carried by said carrier.

10. In a golf game of the class described, a game board having an area included in a playing field, said area being designed to represent a portion of a golf course and including a longitudinal guideway, a flexible driving chain movable beneath said guideway, and an indicator, said indicator comprising a carrier plate having a tooth equipped foot detachably engaged with said driving chain and having a portion extending above the surface of the game board, and a two-part rotatably mounted golf ball representation on the protruding portion of the carrier plate having rolling contact with said board.

11. In a golf game of the class described, a charted game board, guide means cooperable therewith, a propulsion chain operable in said guide means, and a separable indicator movable in the guide means and including a toothed carrier plate received thereby and having a slip connection with the chain for movement therewith, and to permit independent movement of said chain.

12. In a golf game of the class described, a game board having a longitudinally extending guideway, and an indicator movable along said guideway and including a portion representing a golf ball, and a carrier therefor depending into said guideway, together with a propulsion chain movable in said guideway and having loose driving con-

nexion with said portion whereby to provide a desired ratcheting action and to permit said indicator to be bodily lifted out of the guideway for subsequent transfer purposes.

13. In a golf game of the class described, a game board having a predetermined area formed with an open-ended channel-shaped guideway, an indicator comprising a golf ball representation and a segmental toothed portion functioning as a rack, said rack depending into said guideway and said golf ball representation resting on said board, and a flexible ball and pin drive chain movable through said guideway, the rack teeth having separable driving connection with said chain.

14. As a new article of manufacture, a bed plate for use on a game board, including opposed marginal attaching flanges, and depending longitudinally spaced channel-shaped guideways adapted for slidable reception of driving chains, and supporting said chains in a straight line and in a definite spaced relation beneath the game board said guideways being coextensive in length with the plate and open at the ends thereof.

15. In a golf game of the class described, a game board having a playing field provided with guideways, a driving chain movable in each guideway, and a separable indicator including a body portion adapted to be selectively inserted into one of said guideways from the top thereof, said body having a toothed lower edge to provide a slip connection with the chain for movement therewith and to permit independent movement of said chain.

16. In a golf game of the class described, a game board having a playing field provided with guideways, a driving chain movable in each guideway, a separable indicator including a body portion adapted to be selectively inserted into one of said guideways from the top thereof, said body having a toothed lower edge engaging said chain to provide a slip connection therewith, whereby said body is capable of moving with the chain, or the chain permitted independent movement, and a rotatably mounted golf ball representation having rolling contacts with the surface of the board.

17. In a golf game of the class described, a game board having a playing field provided with spaced guideways of channel-like formation and open at both ends, a driving chain movable through each guideway, and supported thereby in definite spaced relation beneath said game board and a separable indicator for each chain, including a body portion adapted to be inserted into one of the guideways from the top thereof, said body having a toothed lower edge to provide a slip connection with the chain, whereby said body and chain can move as a unit or the chain independently of said body.

18. In a golf game of the class described, a game board having a playing field provided with guideways, a driving chain movable in each guideway, a separable indicator including a body portion adapted to be selectively inserted into one of the guideways, and a rotatably mounted golf ball representation having rolling contact with the surface of the board, and a slip connection between the body portion of the indicator and said chain, to permit continued movement of the chain independently of the indicator, when the latter reaches a predetermined position on the field.
- 15 In testimony whereof we affix our signatures.
